DESIGN.

O. RIGHTER.

CARPET.

No. 17,494.

Patented July 26, 1887.

UNITED STATES PATENT OFFICE.

OSCAR RIGHTER, OF PHILADELPHIA, PENNSYLVANIA, ASSIGNOR TO DORAN BROTHERS, OF SAME PLACE.

DESIGN FOR A CARPET.

SPECIFICATION forming part of Design No. 17,494, dated July 26, 1887.

Application filed June 25, 1887. Serial No. 242,541. Term of patent 3½ years.

To all whom it may concern:

Be it known that I, OSCAR RIGHTER, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim—

The design for carpets, as herein shown and described.

OSCAR RIGHTER.

Witnesses:

THEO. A. STEENSON,
GEO. W. GOLDEN.
